UNITED STATES PATENT OFFICE.

EDWARD C. TAYLOR, OF LONGMEADOW, AND CHARLES H. DESAUTELS, OF SPRINGFIELD, MASSACHUSETTS, ASSIGNEES TO THE FISK RUBBER COMPANY, OF CHICOPPEE FALLS, MASSACHUSETTS, A CORPORATION OF MASSACHUSETTS.

AIR-BAG PULLER.

Application filed January 15, 1924. Serial No. 626,438.

To all whom it may concern:

Be it known that we, EDWARD C. TAYLOR, residing at Longmeadow, county of Hampden, State of Massachusetts, and CHARLES H. DESAUTELS, residing at Springfield, county of Hampden, State of Massachusetts, have invented certain new and useful Improvements in an Air-Bag Puller, of which we declare the following to be a full, clear, 10 and exact description.

This invention relates to devices for removing from tire casings the fluid pressure bags on which they have been vulcanized. It has for its object the elimination of hand work in stripping the bags, and the substitution therefor of a compact mechanism operable, with the least possible injurious distortion of the bags, to perform automatically what operations are necessary in opening the 20 tire, distorting the bag, and finally pulling the bag clear of the tire. The manner in which this is done will appear below.

Referring to the drawings,

Fig. 1 is a perspective of the machine showing the initiation of the bag stripping operation;

Fig. 2 is a similar view showing the bag 30 freed to free it partially from the tire; Fig. 3 is a similar view showing the completion of the stripping operation;

Fig. 4 is a similar view of the machine in its stop or inactive position;

Fig. 5 is an end elevation of the machine, partly broken away;

Fig. 6 is a side elevation of the machine, partly broken away;

Fig. 7 is a detail plan of certain operating mechanism, other parts being broken away;

Fig. 8 is a detail elevation similar to a portion of Fig. 6, but showing the parts in a different operative position;

Fig. 9 is a sectional detail on line 9—9 of Fig. 8;

Fig. 10 is a detail similar to Fig. 8, but showing a still different position;

Fig. 11 is a section, similar except in the position of the parts to Fig. 9, taken on line 11—11 of Fig. 10;

Fig. 12 is a detail of the driving clutch;

Fig. 13 is a side elevation thereof;

Fig. 14 is a section on line 14—14 of Fig. 12;

Fig. 15 is a diagrammatic view showing

the path of the end of the spade, showing also positions of the spade and its operating mechanism corresponding to those shown in Figs. 1 and 4;

Fig. 16 is a view similar to Fig. 15, but showing spade positions corresponding to Figs. 2 and 3; and

Fig. 17 is a detail giving illustrative dimensions of the linkage used.

In vulcanizing tire casings of the cord type it is usual to expand the tire into its encircling mold by fluid pressure transmitted through an expansible annular bag. After vulcanization this bag must be removed, a step customarily done by hand. According to the present invention this is done automatically by mechanical means. The manner in which the bag is acted upon will be clearer after the mechanical movements have been described and a discussion of it will be postponed for the present.

The preferred embodiment of the invention may be considered under three main heads: a mechanism for gripping the tire and holding it against the strains incident to the removal of the bag; a tire opening device for exposing a portion of the bag to the stripping arm; and a stripping arm or spade, operated by suitable devices to enter between the bag and the tire, bend the bag towards the center of the tire, and finally force the bag out of the tire at one side. These several groups of mechanism are supported by a base 20 and a framework 21.

The tire opening device, with which the description will be commenced for convenience, is supported upon a pedestal 22 at one end of the base. In the pedestal is formed a vertical guideway 23 within which runs a slide 24 channeled at its top to receive a curved tire support 25. The slide and support are preferably secured together by some releasable connection such as screws in order to permit replacement of the support when the machine is to be used on tires of different wall thicknesses. For a range of tire sizes such as would ordinarily be used on a single machine the wall thickness will not differ enough to require adjustment. The slide is provided with a wrist pin 26 connected by a link 27 with an offset lever 28 (see Figs. 6 and 7) pivoted at 29 to the base 20. Rocking of this lever to raise and

lower the slide in synchronism with the rest of the mechanism is accomplished by a crank device, consideration of which may be best deferred until later.

- 5 Pivoted by studs 30 rotatably secured on lugs 31 projecting from pedestal 22 are hooks 32, shown as four in number. The upper ends of these hooks are bent at 33 to overhang the tire beads, and have wedge 10 ends 34 to enter between the bag and the tire beads. The lower ends are bent to form lugs 35 over which extend abutments 36 carried by the slide 24. When the slide descends the pressure of the abutments will 15 cause the hooks to be swung outwardly against the pressure of springs 37, and thereby permit the insertion or removal of a tire. These hooks, being pivoted to pedestal 22, do not move with the slide and as the latter 20 is elevated they will hold the beads 33 of the tire 39, swinging freely transversely of the tire to conform to the shifting position of the beads as the central part of the tire is forced upwardly (Fig. 1). The upward 25 movement of the slide, coupled with the restraining action of the hooks, causes the bottom part of the tire to be bulged inwardly, forcing the bag 40 to a position in which it is made accessible from the side of the tire. 30 In this position it is ready for the action of the spade.

Before considering the spade and its action, however, the mechanism for holding the tire at its top will be described. In the 35 simplest case, in which only one size of tire is to be handled on the machine, this may be a simple stationary hook, or a hook with a small vertical movement, with its end shaped rather similarly to the hooks 32. 40 The strain on the upper part of the tire is nearly straight downwards, and no other support for it will be needed. In the present case the machine is designed for handling successively and without adjustment 45 tires of different sizes, so that the mechanism is somewhat more highly organized.

The hook 41 which supports the upper part of the tire is in this case formed as a part of a slide 42 running in guideways 43 on the end of a rocking lever 44 pivoted at 45 to the frame 21. The rearward extension of the lever carries a cam roll 46 coacting with a surface cam 47 of a contour to be described. The hook has an upwardly turned 50 lip 48 adapted to enter between the bag and the tire bead, and also a slanting portion 49 adapted to contact with the corner of the bead and insure registration of the point of the hook with the space between the tire and the bag. Attached to the forward end of the lever 44 is a bracket 50 with its upper end bent to receive a threaded rod 51, held 55 adjustably in position by a wing nut 52. A spring 53 connects the rod with the hook 56 slide 42 so as to urge the latter with an ad-

justable tension towards the top of its slide-way. One side of the hook slide is formed with downwardly pointing ratchet teeth 54 (Figs. 9 and 11). Coacting with these teeth, and sliding for this purpose in a hole in the 70 side of the slideway 43, is a pawl 55. A spring 56, located in a recess in the slide-way wall, presses against a lug 57 on the pawl to keep the latter out of contact with the ratchet except when forced in. The 75 preferred mounting for this spring is a screw 59, passing through a hole in the lug and through the spring to keep the parts in alignment.

As the lever 44 is tilted from the position 80 of Fig. 6 to that of Fig. 8 (compare also Figs. 4 and 1), the slide 42 will move with it until the hook strikes the tire bead, and will thereafter, until the pawl is forced into engagement with the ratchet, slide in the ways 85 43, remaining stationary while the lever ascends. This preliminary movement of the lever, ending with the parts in the position of Fig. 8, is caused by a portion 60 of the cam 47 having a uniform rise of relatively 90 steep ascent. In the position of Figs. 8 and 9 two things happen—the cam roll rides on to a portion 61 of the cam of more gradual ascent, and the end of the pawl contacts with a stationary abutment 62 secured to 95 the framework. The abutment (which is shown broken away in Figs. 8 and 10) operates (compare Figs. 9 and 11) to force the pawl into contact with the ratchet, and thereafter the lever and the hook move as a 100 unit. The slight rise of the hook during this latter movement acts to force the lip 48 between the bag and tire bead, and to give to the tire a slight stretch which will hold it firmly during subsequent operations. The cam roll then rides upon a dwell 63 of the cam, preserving the tensioned condition of the tire until such time as the bag has been completely removed.

This device operates to give a uniform 105 tension to the beads of tires as they are successively placed in the machine, whether they are of uniform size or not. Tensioning of the bead is only possible after the pawl has contacted with the abutment 62. 110 This occurs at the position of Fig. 8 in all cases, the cam roll being at this time just entering upon the cam portion of gradual rise. The difference between the hook position at this instant for different tires is 115 indicated by the full and dotted lines in Fig. 8, the full lines representing the position with a smaller tire than the dotted lines. The amount of motion of the hook after this instant is uniform for all tires, 120 being determined by the portion 61 of the cam.

The mechanism for pulling the bag out of the tire so held may now be considered. As 125 it is desirable to keep down as much as pos-

sible the floor space occupied by the machine, and to have the operating parts as simple as may be, the present apparatus has been designed with these ends particularly in view. The stripping arm is formed with a spade 70 adapted to enter between the bag and tire when these are in the positions of Fig. 2, an overhanging piece 71 adapted to bear against the inner periphery of the bag to force it out of the tire, a curved portion 72 permitting clearance of the tire support 25 and attendant mechanism when the arm is in the position of Fig. 3, and a straight portion 73. At the rear end of this straight portion the arm is pivoted at 74 to a rocking lever or thrust arm 75, preferably forked at its upper end to receive it and having rocking bearing at 76 on the base. At the forward end the straight portion of the stripping arm is pivoted at 77 to a connecting rod 78 pivoted in turn to a crank 79 on a shaft 80. Pivoted to the thrust arm at 81 is a connecting rod 82 coupling it to a crank 83 on a second shaft 84. Shaft 80 carries a gear 85 and shaft 84 a gear 86 proportioned so that shaft 80 rotates exactly three times as fast as shaft 84. If the proportions of the linkage described are suitably chosen (cf. the exemplary proportions given on Fig. 17) the end of the spade will be caused to follow the path shown at 87 in Figs. 15 and 16. The detailed operation of the cranks and connections need not be described since they appear in these figures more clearly than in words.

From the full line position of Fig. 15, which is one in which the machine can conveniently be stopped, the spade is moved by its controlling linkage to the dotted line position, first withdrawing to the peak 88 of the curve. The approach of the spade to the tire is by this linkage made almost in a straight line (89 in Fig. 15). Thus the first operative motion of the spade is a direct insertion from one side between the tire and air bag. This position is shown in Fig. 1 and in dotted lines in Fig. 15. As soon as the spade is well inserted under the air bag continued rotation of the cranks causes it to rise, its end following still the path shown in Figs. 15 and 16. Using the proportions specified the rise will be rather abrupt, as indicated at 90, continuing until the spade has reached the peak 91. This condition is shown in Fig. 2 and in full lines in Fig. 16. The bag is by this rise of the spade folded upon itself about the spade, and is thereby freed from the tire at the bottom. The spade now descends as a 92, moving at the same time outwardly so that the bag will be carried out of and clear of the tire at one side. Sufficient drop is given to the spade to insure that the bag will be completely freed from the tire, the exact

amount being immaterial. During the drop the stripping arm acts upon the bag through the overhanging piece 71 aided initially by the grip of the folded bag around the spade itself. The fold in the bag will first 70 straighten out; then, as the spade continues to go lower, the bag will pull out of the sides of the tire, finally coming completely out with a snap that will free itself from the spade as indicated in Fig. 3. 75 The bag being thus freed from the tire, the spade again rises, nearly retracing its original path as it travels along line 93 to peak 94. In going from this position to the stop position of Figs. 4 and 15 80 the path of the spade is immaterial as long as it does not interfere with any of the other mechanism, the drop 95 taken in the present embodiment being due to the nature of the crank and link mechanism used. The time taken for this travel is utilized in returning the other parts to their normal positions ready for the removal of the tire from which the bag has been removed and the substitution of a fresh one. 90

The machine is for convenience provided with a clutch mechanism which will, upon a single actuation of the control, carry the mechanism through one cycle, and stop it automatically in the position of Fig. 1. Any suitable clutch mechanism of this type may be employed, that to be described being of a type commonly used upon punch presses. Motive power for all the described mechanisms is derived from an electric motor 100 100 (Fig. 7), the shaft of which carries a pinion 101 meshing with a gear 102 on a shaft 103 journaled in the base. A worm (not shown) on this shaft meshes with a worm-wheel 104 loose on the shaft 84 upon which the crank 105 83 is carried. Upon the hub of the worm-wheel are mounted a series of studs 105 (Figs. 12, 13, and 14) which bear against the side of the large gear 86, serving both as elements of the clutch mechanism and as spacing devices holding the worm-wheel against endwise shifting in one direction. The hub 106 of the large gear is apertured to receive a sliding pin 107, normally pressed toward the studs by a spring 108. In one side of the 110 pin is a groove into which the tapered end 109 of a clutch finger 110 may enter. This finger is pivoted at 111 to the machine base and normally is drawn towards the axis of the gear by a spring 112. Connecting the 115 finger, which is formed as a bell-crank, with a lever 113 (Fig. 7) pivoted at an intermediate point to the base, is a link 114. The lever extends in a generally oblique direction underneath the machine, terminating in a 120 treadle 115.

In the operation of the machine the motor 100 runs continuously. When a tire has been placed in position the treadle is depressed by the operator. This swings the tapered 125

- end of the clutch finger out of the groove in the pin. The pressure of the spring forces the pin into the path of that one of the studs 105 which may be next to come by.
- 5 If the treadle is now released the end of the clutch finger is swung by the spring 112 into the path of the pin. When the shaft has completed its revolution, causing the machine to perform one complete cycle of operations, the edge of the groove in the pin will ride up the tapered surface of the clutch finger, withdrawing the pin from contact with the driving studs and stopping the machine.
- 10 15 The shaft 84 on which the clutch mechanism is situated also furnishes the power for the tire holding and opening devices. The shaft 116 carrying cam 47 is fitted with a sprocket 117 connected by a chain 118 with a sprocket 119 fixed to the shaft 84. At the other end of the crank shaft 84 is a second crank 120 carrying at its end an anti-friction roll 121. The rear end of the rocking lever 28 operating the tire opening device is finished at 122 and 123 to provide flat bearing surfaces, and has a cylindrical bearing surface 124 of a radius equal to that of the crank plus that of the cam roll, so that while the crank is moving over that much of its travel no movement of the rocking lever will occur. This construction gives a quick rise of the tire support 25, occurring in the passage of the spade from the full to the dotted line position of Fig. 15; a dwell during which the bag is pulled upwardly; and a lowering of the tire support during the latter part of the downward movement of the spade on line 92.
- 20 25 30 In Fig. 17 dimensions of the cranks and linkage operating the spade have been given for convenience in laying out the machine. Complex linkages of this sort give quite different results if their proportions be changed, and while the invention is not restricted to the form of linkage shown, it has been thought desirable for clearness to give one example of the dimensions of the critical

parts in the interest of completeness of disclosure.

Having thus described our invention, we claim:

1. In a machine for pulling bags out of tire casings, tire holding means, a device for opening the tire, and a spade arm provided with mechanism for forcing it between the tire and bag, raising the bag to buckle it inwardly, and then forcing the bag out one side of the tire.

2. In a machine for pulling bags out of tire casings, a device for opening the tire, and a single means for initially separating the tire and bag at the point of opening and thereafter pulling the bag free of the tire.

3. In a machine for pulling bags out of tire casings, tire holding means, a device for opening the tire, a spade arm, a rocking thrust arm pivoted to one end of the spade arm, a crank, a link connecting the crank with the thrust arm, a second crank, means for rotating the second crank at a speed three times that of the first crank, and a link pivotally connecting the second crank with an intermediate point on the spade arm.

4. In a machine for pulling bags out of tire casings, a device for holding and opening the tire, a device for engaging the opposite side of the tire and giving to tires of varying diameter a uniform stretch, and means for grasping the bag and pulling it from the tire.

5. In a machine for supporting tire casings, so that internal pressure bags may be pulled therefrom, means for holding one side of the tire, a hook adapted to engage the bead edge of the tire on the opposite side, a movable member in which the hook slides, a spring acting to urge the hook towards the tire bead, means for moving the member, and a device for locking the hook to the member at a predetermined point in the movement of the latter.

EDWARD C. TAYLOR.
CHARLES H. DESAUTELS.

DISCLAIMER.

1,535,382.—*Edward C. Taylor, Longmeadow, and Charles H. Desrutes, Springfield, Mass. AIR-BAG PULLER.* Patent dated April 28, 1925. Disclaimer filed January 14, 1928, by the assignee, *The Fisk Rubber Company*.

Hereby enters this disclaimer to that part of the claim in said specification which is in the following words:

“2. In a machine for pulling bags out of tire casings, a device for opening the tire, and a single means for initially separating the tire and bag at the point of opening and thereafter pulling the bag free of the tire.”

[*Official Gazette February 7, 1928.*]
